INCENDIARY BOMB TRAP

William C. Scull, Darling, Pa.

Application June 5, 1942, Serial No. 445,934

1 Claim. (Cl. 294—55)

This invention relates to new and useful improvements in means for handling fallen incendiary bombs.

The principal object of the present invention is to provide a trap-like structure whereby an incendiary bomb can be trapped or captured and carried to a safe place where it can be permitted to consume itself.

Another important object of the invention is to provide a device for handling active incendiary bombs in a convenient and safe manner.

These and other important objects and advantages of the invention will become apparent to the reader of the following specification.

In the drawings:

Figure 1 is a top plan view of the trap.

Figure 2 is a side elevational view.

Figure 3 is a front elevational view.

Figure 4 is a section on the line 4—4 of Figure 3.

Figure 5 is a longitudinal sectional view taken substantially on the line 5—5 of Figure 4.

Referring to the drawings wherein like numerals designate like parts, it can be seen that numeral 5 denotes an elongated handle which is secured by metal straps 6, 7 at its forward end to an elongated rectangular-shaped box structure 8. This box structure is open at its front side where a door 9 is secured in place by hinges 10. As is apparent in Figures 4 and 5, the box-like structure 8 and the door 9 have an asbestos or other fire-proof lining 11.

Mounted upon the box-like structure 8 is a bracket 12 supporting a bellcrank 13, the bellcrank being fulcrumed to the bracket 12 at its heel portion and by a suitable means 14. A link extends from one end of this bellcrank 13 to a lug 15 secured to the door 9.

From the other end of the bellcrank 13 extends a rod 16 which connects to an intermediate portion of a hand lever 17 swingably secured to a bracket 18, the latter, in turn, being secured by bolts or the like 19 to the elongated handle 5.

A cross bar 20 extends longitudinally on the lower portion of the door 9, the ends of which project beyond the ends of the door and have apertures to receive the ends of tension springs 21.

The tension springs 21 extend to connect to lugs 22 on the end walls of the box-like structure 8.

It can be seen, that in approaching a bomb, the hand lever 17 is pulled back, to open the door 9 and when the trap has been positioned with the bomb under the door 9, the hand lever 17 is released, and the spring 21 will snap the door 9 closed, kicking the bomb into the box-like structure 8.

15 The box-like structure can now be carried to a window or out of doors to a safe place where it can be released.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

In a device for handling incendiary bombs, a pole-like handle, an elongated rectangular box structure fixed to one end of the handle to extend lengthwise across the same and having a hinged downwardly closing front door, means to yieldingly close said door comprising a bar extending along the bottom edge of the same beyond the ends of said structure, a pair of coil springs at opposite ends of the structure attached to said structure and to the opposite ends of said bar, and means to open the door comprising a pivoted lever upstanding from said handle, a bell crank pivotally mounted on top of said structure in upstanding position, a rod operatively connecting said lever to one arm of the bell crank, and a link operatively connecting the other end of the bell crank to the door in front thereof.

WILLIAM C. SCULL.
